UNITED STATES PATENT OFFICE.

FRANKLIN E. EMERT, OF YOUNGDALE, PENNSYLVANIA.

INTERNAL-COMBUSTION-ENGINE TIMER.

Application filed August 1, 1924. Serial No. 729,641.

To all whom it may concern:

Be it known that FRANKLIN E. EMERT, a citizen of the United States of America, residing at Youngdale, in the county of Clinton and State of Pennsylvania, has invented new and useful Improvements in Internal-Combustion-Engine Timers, of which the following is a specification.

The purpose of the invention is primarily to provide a timer with a moving contact, the life of which will be substantially the same as that of the timer itself or of the car on which the device is used, and to arrange such moving contact so that it will not be subject to chattering and so that it may be automatically fed to compensate for wear due to use.

With this purpose in view, the invention consists in the construction and combination of parts of which a preferred embodiment is illustrated in the accompanying drawings, wherein:

Figure 1 is an elevational view, partly broken away, illustrating the invention.

Figure 2 is a side elevational view, partly in section, of the timer head detached.

Figure 3 is a vertical sectional view of the structure of Figure 2 in the plane of the axis of the brush.

Figure 4 is an edge elevational view of the structure of Figure 2.

Figure 5 is a sectional view on the plane indicated by the line 5—5 of Figure 2.

The moving contact consists of a metal brush 1 traversing the contacts 2 of the stationary member of the timer. The brush is carried by the rotary head 4 which is mounted on the cam shaft 5, the head being provided with a hub 6 for connection to the cam shaft. The brush occupies the position of a chord and is preferably cross sectionally angular as shown, being slidably mounted in a slide bearing 7 cross sectionally conforming to the cross sectional contour of the brush and provided interiorly with spaced ribs 8 on which the brush slides and which reduces the friction to a minimum.

In order that the brush may be the full length of the chord which it defines and yet be yieldingly impelled toward the contacts 2, a reel is provided at the forward end of the brush consisting of a grooved pulley 9 on which a strap 10 reels, one end of the strap being connected to the pulley, as by a pin 11 engaging slots 12 formed in the op-

posite flanges of the pulley. One end of the strap is connected to the pin and the remaining end is formed with an eye 14 engaging a lateral pin 15 mounted on the brush near the rear end of the latter and projecting through a slot 16 in the slide bearing. As the pulley rotates, the strap is reeled on the same and the brush advanced, the pull being always from the rear end of the brush.

In order to provide for the rotation of the pulley, the latter is formed with a hub portion 17 grooved, as at 18, for the reception of a flat spiral spring 19, one end of which is connected with the hub and the other engaged with a pin 20 mounted on the primer head. The spring tending to unwind, tends to rotate the pulley in a direction to reel the strap thereon and therefore advance the brush toward the stationary contact with which it is held yieldingly in engagement by the spring 19.

The brush being offset from the center of the head, its relation with the stationary contact is tangential and thus the chattering incident to a radial brush is eliminated. Also, the relatively great length of the slide bearing and the arrangement of the means for impelling the brush provides for the use of a brush the full length of the bearing and that provides another insurance against any tendency to cause chattering.

The rotary head is locked on the cam shaft by means of a radial pin 21 and when the latter is seated, the exposed end is covered by a latch plate 22 pivotally mounted on the angular plate 23 carried by the rotary head.

In order to protect the strap and the pulley, a washer 24 is mounted just behind the hub of the head. This serves to retain the latch plate in place and also operates as a guard for the strap and the pulley.

The invention having been described, what is claimed as new and useful is:

1. A timer comprising a rotary head, a slide bearing mounted thereon, a brush mounted in the slide bearing and longitudinally movable therein, a reel comprising a grooved pulley and connected hub, a coil spring terminally connected with the hub and a point on the head to impart rotary movement to the hub, and a strap reeled on the pulley and terminally connected with the brush, the brush at its rear end being provided with a lateral pin with which one

extremity of the strap engages and the bearing being provided with a longitudinal slide slot which said pin traverses.

2. A timer comprising a rotary head, a slide bearing mounted thereon, a brush mounted in the slide bearing and longitudinally movable therein, a reel comprising a grooved pulley and connected hub, a coil spring terminally connected with the hub and a point on the head to impart rotary movement to the hub, a strap reeled on the pulley and terminally connected with the brush, the brush at its rear end being pro-

vided with a lateral pin with which one extremity of the strap engages and the bearing being provided with a longitudinal slide slot which said pin traverses, the head being provided with a hub for mounting on a cam shaft, and a guard washer disposed in abutting relation to the hub and in shielding 15 relation to said strap and the adjacent side pulley in the unreeled position of the strap. 20

In testimony whereof he affixes his signature.

FRANKLIN E. EMERT.
